US00D991892S

(12) **United States Design Patent** (10) **Patent No.:** **US D991,892 S**
(45) **Date of Patent:** **** Jul. 11, 2023**

(54) **ON LINE SWITCH CONTROLLER**

(71) Applicant: **Keyong Song**, Zhejiang (CN)

(72) Inventor: **Keyong Song**, Zhejiang (CN)

(**) Term: **15 Years**

(21) Appl. No.: **29/763,995**

(22) Filed: **Dec. 28, 2020**

(30) **Foreign Application Priority Data**

Dec. 10, 2020 (CN) 202030762535.9

Assistant Examiner — Leah E Hoeferkamp

(57) **CLAIM**

The ornamental design for an on line switch controller, as shown and described.

DESCRIPTION

FIG. 1 is a perspective view of an on line switch controller showing my new design;

FIG. 2 is a front view thereof;

FIG. 3 is a back view thereof;

FIG. 4 is a left view thereof;

FIG. 5 is a right view thereof;

FIG. 6 is an enlarged top view thereof;

FIG. 7 is an enlarged bottom view thereof;

FIG. 8 is an enlarged partial view of area '8' in FIG. 2; and, FIG. 9 is an enlarged partial view of area '9' in FIG. 3.

The dash-dash broken lines and the unshaded areas within them in the drawings are for the purpose of illustrating portions of the article that form no part of the claimed design. The dot-dash broken lines in the drawings are for the purpose of illustrating the boundaries of the portions shown enlarged in the views, and form no part of the claimed design.

1 Claim, 9 Drawing Sheets
